[57] **CLAIM**

The ornamental design for a wood carrier, as shown and described.

DESCRIPTION

FIG. 1 is a perspective view of a wood carrier showing my new design;

FIG. 2 is a front elevational view, the rear elevational view being substantially a mirror image thereof;

FIG. 3 is a side elevational view thereof; and

FIG. 4 is a top plan view thereof.

FIG. 2

FIG. 3

FIG. 4
